UNITED STATES PATENT OFFICE

94,365

DESIGN FOR A COMBINED ASH RECEPTACLE AND MATCH HOLDER

Edward Schultz, Chicago, Ill., assignor to The Nagel-Chase Mfg. Co., Chicago, Ill., a corporation of Illinois

Application May 14, 1934, Serial No. 51,783

Term of patent 7 years

To all whom it may concern:

Be it known that I, Edward Schultz, a citizen of the United States, residing in Chicago, in the county of Cook and State of Illinois, have invented a new, original, and ornamental Design for a Combined Ash Receptacle and Match Holder, of which the following is a specification, reference being had to the accompanying drawing, forming a part thereof—

I claim:

The ornamental design for a combined ash receptacle and match holder, as shown.

EDWARD SCHULTZ.
